[57] CLAIM

The ornamental design for a electrical cord protector, as shown and described.

DESCRIPTION

FIG. 1 is a perspective view of a electrical cord protector showing my new design;

FIG. 2 is a front elevational view thereof, the rear view being a mirror image;

FIG. 3 is a left side elevational view thereof;

FIG. 4 is a right side elevational view thereof; and,

FIG. 5 is a top plan view thereof, the bottom plan view being a mirror image.

The dashed lines shown FIG. 1 and FIG. 5 represent an electrical extension cord for use with the present design, and form no part of the claimed invention.

1 Claim, 2 Drawing Sheets

FIG. 5
